2 SHEETS - SHEET 2.

UNITED STATES PATENT OFFICE.

HERMAN W. SCHATZ, OF NORWOOD, OHIO.

ELECTRIC DRIVING MEANS FOR DRILLING MACHINERY.

1,379,782.

Specification of Letters Patent. Patented May 31, 1921.

Application filed June 9, 1917. Serial No. 173,800.

To all whom it may concern:

Be it known that I, HERMAN W. SCHATZ, a citizen of the United States, residing at Norwood, in the county of Hamilton and State of Ohio, have invented certain new and useful Improvements in Electric Driving Means for Drilling Machinery, of which the following is a specification.

My invention relates to electric driving means for drilling machinery.

It is the object of my invention to provide driving means for a drilling machine, comprising an electric motor mounted upon the drill-arm and distanced from the tool-slide, and manual speed controlling means therefor moving with the tool-slide and positioned convenient to the operator of the machine.

It is the further object of my invention to so mount the electric motor upon the drill-arm of the machine, as to counteract the weight of said arm and the tool-slide supported thereby and to move with the arm when the latter is adjusted, and whereby frictional resistance in moving the drill-arm up and down or swinging it about the axis of the column is minimized, and whereby, further the driving connection between the motive power and the cross-shaft extending lengthwise of the drill-arm is simplified.

In the present exemplification of my invention, the tool-slide is adjustable laterally upon the radial supporting arm, and the electric motor for operating the tool-slide on the tool-slide is also mounted on said arm, the speed of the electric motor being controlled by manual controlling means moving with the laterally adjustable tool-slide, the said manual controlling means having adjustable mechanical connections with the electric controlling means of the electric motor, instance as a drum-type controller mounted on said arm.

It is a further object of my invention to so mount a motor upon the swinging drill-arm of a radial drilling-machine, as to permit the motor to be moved with the drill-arm for all radial positions of the latter, and enabling the drill-arm with the motor mounted thereon to be moved about a complete circle without obstruction so as to present the tool for operation at any portion of a complete circle.

The invention will be further readily understood from the following description

and claims, and from the drawings, in which latter:

Figure 1 is a front elevation of a radial drilling machine, partly broken away, having my invention applied thereto. 60

Fig. 2 is a plan view of the same.

Fig. 3 is a rear elevation of the same, partly broken away.

Fig. 4 is a vertical section of the same, taken on the line 4-4 of Fig. 1. 65

Fig. 5 is a plan view detail of the same, partly in section, taken on the line 5-5 of Fig. 4; and,

Fig. 6 is an axial sectional detail of the same taken on the line 6-6 of Fig. 4. 70

The drilling machine, which is exemplified as embodying my invention, includes a usual base 11, from which a usual post 12 extends upwardly in rigid relation, the post being surrounded by a usual column 13 shown as a rotary column, having a drill-arm 14 mounted thereon, as by a bearing 15 surrounding the column. The base may extend from one side of the post, or may surround the post in the form of a circular 80 base.

The drill-arm is arranged to be raised and lowered to adjustable positions on the column by suitable mechanism instanced as an upright screw-rod 16 having threaded connection with a nut 17 fixedly located in the drill-arm. The adjusting rod is journaled at its lower end in a bearing 21 and extends lengthwise of the supporting column. It is arranged to be rotated in either direction for either raising or lowering the drill-arm, and to be stopped or started as desired, in any suitable or well-known manner, under the manual control of the operator. After adjustment, the bearing is 90 clamped to the column, as by usual clamps 25, it being understood that the bearing 15 is a clamp-bearing which is unclamped prior to adjustment on the column and clamped in position to the column after adjustment. 100

The supporting column is arranged to be rotated so as to position the drill-arm at any desired radial position, preferably throughout the entire extent of the three hundred and sixty degrees of a circle, for 105 positioning the drill-arm either with relation to a table 41 of the base, or, if desired, to the floor about the drilling machine on which the work may be placed, or to a suitable circular base about the post. 110

This is shown as accomplished by having the column supported by a usual bearing 42 about the post 12, the bearing comprising an annular row of anti-friction rollers 43 about the post. The bearing is exemplified as a clamp-bearing so as to clamp the column in adjusted position to the post by means of a usual bearing clamp 44 provided with an operating handle 45. An upper annular ball 10 bearing 40 between the post and column aids in rotation of the column.

A tool-slide 46 is laterally adjustable upon the drill-arm 14. The lateral adjustment of the tool-slide may be accomplished by providing the drill-arm with a rack 47, adapted to be engaged by a pinion 48, journaled on the tool-slide and manually actuated through suitable gearing by a hand-wheel 49 upon the tool-slide, for laterally adjusting the 20 slide upon the drill-arm.

In practice, the drill-arm, in present usual constructions, which extends radially from supporting column 13, and the tool-slide which is adjustable laterally thereon, are 25 heavy, and exert a heavy strain on the bearing 15 of the drill-arm about the column. This strain is increased as the tool-slide is adjusted toward the free end of the radial arm, owing to the increase in leverage at the 30 column. As a result of this strain, there is a constant tendency toward inaccuracy in the work performed by the machine, owing to the tendency of the drill-arm to sag, which results in the drill-spindle 51, journaled in 35 usual manner in the tool-slide, moving out of parallelism with the vertical axis of the column, assuming the drill-spindle to be in normal up and down position.

In order to avoid these objections and the 40 consequent inaccuracy in work, and to provide for more ready adjustment of the drill-arm on the column, and to minimize frictional resistance between the bearing of the drill-arm and the column, I provide the drill-arm 45 with a bracket 52 extending laterally at the other side of the column from that at which the drill-arm proper is located, so that the drill-arm extends from one side of the bearing about the column, and the bracket 50 extends from the other side of said bearing about the column, preferably diametrically opposite to the drill-arm proper. An electric motor 53 for operating the drill-spindle, is mounted upon this bracket, the weight of 55 the bracket and motor acting counter to the weight of the drill-arm and spindle, at opposite sides of the column, for substantially balancing the weight supported by the column.

60 The electric motor is arranged to operate the usual driving and feeding means which are mounted on the tool-slide for operating the drill-spindle, preferably through the usual drive-shaft 35 extending lengthwise of 65 the radial drill-arm, which operates a usual

train of gearing 54 on the tool-slide for starting or stopping the drill-spindle and for rotating the same in either direction, and for feeding the same, a portion of this train of gearing being instanced as bevel-gears 55, 56, 70 having usual selective clutch connection with a sleeve 57 about the shaft 35, as by a handle 50, said sleeve having usual spline-connection 58 with said shaft, for being operated by said shaft, in usual manner, at 75 all adjusted positions of the tool-slide. The armature-shaft 59 of the electric motor has a pinion 60 thereon which meshes with a gear 61 on the drive shaft 35 for operating the same. The drive-shaft is journaled in a bearing 62 on the drill-arm adjacent to the motor and in a bearing 63 on an arm 64 rigidly secured at the outer end of the drill-arm. The motor is rigidly secured to the bracket 52, as by bolts 65.

85 The speed of the electric motor is controlled by a suitable electric control device, exemplified as a rotary rheostat or drum controller 71, which electrically controls the speed of rotation of the armature shaft 59 of the electric motor. The drum controller is shown secured to the motor-frame by bolts 72. The electric control device of the electric motor is manually controlled by manual controlling means moving laterally with the 90 tool-slide, the manual control device having mechanism extending therefrom to the electric control device so arranged that said connection is effective for moving said electric control device at all adjusted operative positions of the tool-slide so as to start or stop or vary the speed of the motor by manipulation of said manual control device at the operator's position in front of the tool-slide, regardless of the operative position to which 95 the tool-slide is adjusted.

100 The drum controller may be of usual construction for controlling the speed of the armature shaft of the electric motor by movement of the movable member of the 110 drum controller, instanced as a rotation of the shaft 73 of the drum controller, which selectively effects coaction between various electric contacts 74, 75, in the drum controller for varying the speed of the motor 115 and stopping or starting the same.

120 The controlling means for the electric control device is exemplified as comprising a shaft 76, extending lengthwise of the radial drill-arm and adapted to be manually rotated by a shaft 77, which is shiftable with the tool-slide along the radial drill-arm.

125 Instancing this arrangement, the shaft 77 may be journaled in bearings 68, 78, of brackets 69, 79, secured to the tool-slide. A shiftable driving connection is formed between shafts 77 and 76, which may comprise a bevel-gear 80 fast upon shaft 77 and meshing with a second bevel-gear 81, having 130

spline-connection with shaft 76, as shown at 82. The bevel-gear 81 having spline-connection with shaft 76, is arranged to be moved lengthwise along the shaft so as to remain 5 in mesh with bevel-gear 80, when the tool-slide is adjusted laterally upon the drill-arm. This is preferably accomplished by journaling the hub 83 of bevel-gear 81 in a bearing 84 of the bracket 79 which is se- 10 cured to the tool-slide, the bearing 84 being located between a shoulder 85 on said gear 81 and a collar 86 secured to its hub 83.

Shaft 77, which is thus arranged to rotate shaft 76 for controlling the rotation of the 15 movable member of the electric control device, is exemplified as provided with a hand-wheel 88, which is preferably positioned at the front of the tool-slide, convenient to the operator of the machine 20 when standing in usual position in front of the tool-slide of the machine. The hand-wheel is instanced as provided with a graduated dial-face 89, which is rotatably adjustable with relation to a fixed indicator 25 finger 90 upon the tool slide by manual rotation of the hand-wheel. The graduations 91 of the dial-face, coöperating with the fixed indicator, are preferably arranged to indicate the positions to which shaft 76 must 30 be rotated in order to stop rotation of the armature-shaft of the electric motor, or to cause the same to rotate at selective variable speeds.

The shaft 73 of the electric control device 35 has a sprocket-wheel 94 fixed thereto. A sprocket-wheel 95 is fixed to the shaft 76, a sprocket-chain 96 being received about the sprocket-wheels 94, 95, for actuating the movable part of the electric control device 40 and thereby effecting the starting or stopping of the motor or varying its speed.

My improved device provides simple driving means for the drill-spindle, mounted on and moving with the drill-arm for enabling 45 the drill-arm to be moved about a complete circle without obstruction, and provides simple control means for the electric motor at all times within easy reach of the operator.

50 Having thus fully described my invention, what I claim as new and desire to secure by Letters Patent, is:

1. In a drilling machine, the combination of a column, a drill-arm adjustable up and 55 down on said column, a tool-spindle adjustable laterally on said drill-arm, an electric motor mounted on said drill-arm having operative connection with said tool-spindle for operating the same, an electric 60 control device on said drill-arm distanced from said tool-slide, and a manual control moving with said tool-slide for said electric control device for operating the latter.

2. In a drilling machine, the combination 65 of a column, a drill-arm adjustable up and

down on said column, a tool-slide adjustable laterally on said drill-arm, a drill-spindle journaled on said tool-slide, a shaft extending lengthwise of said drill-arm for operating said drill-spindle, an electric motor on said drill-arm for driving said last-named shaft, an electric control device supported by and moving with said drill-arm for controlling the speed of said electric motor, a second shaft extending lengthwise 70 of said drill-arm having operative connection with said electric control device for operating the same, and an operating part moving with said tool-slide, said operating part having driving connection with 75 said second shaft for rotating said second shaft by means of said operating part at the various positions of adjustment of said tool-slide.

3. In a drilling machine, the combination 80 of a column, a bearing movable up and down on said column, a drill-arm extending from one side of said bearing, a bracket extending from the opposite side of said bearing, a tool-slide, means for adjusting said tool-slide laterally on said drill arm, an electric motor supported by said bracket, an electric control device moving with said bearing for controlling the speed of said motor, a shaft extending lengthwise of said 85 drill-arm, a manually operated part moving with said tool-slide, gearing having rotative connection with said shaft and slidable with said manually operated part and tool-slide lengthwise of said shaft, and operating connecting means between said shaft and electric control device.

4. In a drilling machine, the combination 90 of a column, a bearing thereon adjustable up and down, a drill-arm extending from one side of said bearing, a bracket extending from the other side of said bearing, a tool-slide slidable laterally on said drill-arm, an electric motor supported by said bracket, an electric speed control device 95 for the latter moving with said bearing, a shaft passing said column having operative connection with said electric speed control device, and a manually operated part mounted on and movable with said tool-slide arranged for rotating said shaft at all 100 adjusted operative positions of said tool-slide.

5. In a drilling machine, the combination 105 of a column, a bearing on said column adjustable up and down, a drill-arm extending from one side of said bearing, a bracket extending from the other side of said bearing, a tool-slide slidable laterally on said drill-arm, a drill-spindle journaled thereon, 110 means for sliding said tool-slide laterally on said drill-arm, an electric motor supported by said bracket, an electric speed control device for the latter moving with said bearing, a shaft passing said bearing and jour- 115 120 125 130

naled on said drill-arm, gearing between said shaft and electric speed control device for operating the latter, and a hand control moving with said tool-slide and having operative slide connection with said shaft for rotating the same.

5 In testimony whereof I have hereunto

signed my name in the presence of two subscribing witnesses.
